E. HARDT.
BINDING HOLDER.
APPLICATION FILED DEC. 26, 1912.

1,178,070.

Patented Apr. 4, 1916.

UNITED STATES PATENT OFFICE.

EMIL HARDT, OF PATERSON, NEW JERSEY, ASSIGNOR TO HELLER HARDT HAT BAND CO., OF PATERSON, NEW JERSEY, A CORPORATION OF NEW JERSEY.

BINDING-HOLDER.

1,178,070.

Specification of Letters Patent. Patented Apr. 4, 1916.

Application filed December 26, 1912. Serial No. 738,535.

To all whom it may concern:

Be it known that I, EMIL HARDT, a subject of the Emperor of Germany, residing in the city of Paterson, in the county of

5 Passaic and State of New Jersey, have invented certain new and useful Improvements in Binding-Holders, of which the following is a full, clear, and exact description, such as will enable others skilled in the art 10 to which it pertains to make, construct, and use the same, reference being had to the accompanying drawings, and to letters of reference marked thereon, forming a part of this specification.

15 My invention relates to improvements in binding holders or cards, and has for its object to provide a holder or card which will hold the binding in such a manner as to preserve its original shape.

20 Binding tapes, bands or ribbons in general use for hats and similar articles, are woven so as to provide said tape, band or ribbon with an edge which is shorter than the other edge, said binding adapted to be 25 bound to the edge of a stiff hat brim in a manner that will save stitching, cause the binding to lie flat against the brim, and thus prevent puckering. It frequently happens that after the binding leaves the factory, it 30 is carried in stock for a considerable length of time before it is applied to the hats, and unless the same is properly wound upon a holder especially designed for that particular purpose, the short edge of the ribbon becomes 35 distended or stretched, rendering the same practically useless.

In the accompanying drawings which form a part of this application, I have shown a preferred form of my invention, in 40 which—

Figure 1 represents a plan view of my improved holder or card upon which the hat binding or other flexible materials are to be placed. Fig. 2 represents an edge view of 45 the same. Figs. 3 and 4 represent respectively, a plan and an edge view of my improved holder or card with the hat binding placed thereon, the binding being shown in dotted lines in Fig. 4. Fig. 5 represents a 50 plan view of a piece of hat binding to be placed on my improved card, illustrating said binding as provided with a short and a long edge. Fig. 6 represents an enlarged

fragmentary sectional view taken on lines *a*—*a* of Fig. 1 and Fig. 7 represents a perspective view of a modified form of my improved holder. 55

Similar letters of reference refer to like parts throughout the specification and drawings. 60

In the drawings, *a* represents the holder or card upon which the binding or other materials are to be placed or coiled, and which has suitable notches *b*, *b* in its ends, which act or aid to properly position and hold the binding upon the same. By the term holder or card, I do not limit myself to a card of any particular material, for any material may be used which is suitable for the purpose, such as paste-board, wood, metal and the like, and therefore, when I use the term holder or card, I refer to any relatively thin means which is suitable for the purposes described. The notches *b* as illustrated, are provided with three sides, lettered respectively *c*, *d* and *e*, the side *e* being preferably made parallel with one of the longitudinal sides *f* of the holder or card *a*. The opposite side of the notch, namely, *c*, is given a shape corresponding approximately to the shape of the short edge of the binding, so that when the binding is wound on the holder or card, the sides *c* of the notches *b*, and the short edge of the binding constitute a continuous line as indicated at *k* in Fig. 3 of the drawings. 75

d represents the bottom side of the notch, which connects the sides *c* and *e*, and which bottom side *d* is preferably curved as shown. 80

As heretofore stated, in order to preserve the short edge of the binding, the same must not in any wise become distended or stretched, but the long edge of the binding or ribbon can be subjected to a certain amount of stretch advantageously, inasmuch as any stretching which takes place on the long edge of the binding improves the opposite or short edge thereof. Therefore, in order to impart to the long edge some additional stretch, during the time that the same is wound upon the holder or card *a*, and during the time the binding remains on the holder or card, I provide said holder with a series of projections *g*, which tend to stretch the long edge of the binding. These projections in the preferred form are integral por- 90 95 100 105

tions of the holder or card, pierced out of the material from which the holder is made, and are so arranged as to be formed on both sides of the card, as clearly illustrated in 5 Figs. 2 and 4 of the drawings.

The side *d* of the notch, in its preferred form, as illustrated in Fig. 2 of the drawings, is made by cutting the sides *c* and *e* a trifle below the edge *d* as indicated at *h* and 10 *j*, and reinforcing the sides by curling the material thereof over in any convenient or suitable manner, so as to provide a rounded edge, over which the binding or ribbon passes. The rounded edge of the notch 15 serves the binding or ribbon and prevents the same from cracking.

In Fig. 7 of the drawings, I have shown a modified form of my improved holder, the 20 operation and principle of which is identical with the structure shown in Fig. 1, with the exception that instead of employing a card provided with notches, I employ an elliptical holder *l*, made from any suitable material, either hollow or solid, the 25 rear end of which is larger than the front end so that binding tapes, bands, ribbons or other flexible material wound thereon will maintain their original shapes.

I believe that I am the first to use a 30 holder so formed that the short edge of the flexible material wound on said holder will not be stretched, but will retain its original shape, and therefore desire to claim it broadly.

35 Experience has demonstrated that the invention above described is a highly efficient one, and while the device described is the preferred embodiment of my present invention, I do not care to restrict myself to the 40 exact details of construction, combination, and arrangement herein set forth, it being obvious that minor variations thereof not involving the exercise of invention may be made by any skilled mechanic, and such departure 45 from what is herein described and claimed not involving invention, I consider as within the scope and terms of my claims.

I claim:

1. The improved holder for hat bindings 50 and the like, said binding being provided with a short and a long edge, consisting of a card provided with means in the opposite

ends of said card adapted to receive said binding and retain its original shape.

2. The improved holder for hat bindings 55 and the like, said binding being provided with a short and a long edge, consisting of a card having a receiving notch in each end to receive said binding and retain its original shape.

3. The improved holder for hat bindings 60 and the like, said binding being provided with a short and a long edge, consisting of a card having notches in the opposite ends thereof to receive said binding, said notches 65 being provided with curved sides to engage with the short edge of said binding.

4. The improved holder for hat bindings 70 and the like, said binding being provided with a short and a long edge, consisting of a card provided with oppositely arranged binding receiving notches provided with curved sides and bottoms, said curved sides 75 designed to engage with the short edge of said binding.

5. The improved holder for hat bindings 80 and the like, said binding being provided with a short and a long edge, consisting of a card provided with oppositely arranged binding receiving notches, said notches being of approximately the same width as the binding and are provided with curved sides and reinforced bottoms, said curved sides 85 designed to engage with the short edge of said binding and means formed on the face of the card designed to engage with the long edge of the said lining.

6. The improved holder for hat bindings 90 and the like, said binding being provided with a short and a long edge, consisting of a card provided with oppositely-arranged binding receiving notches, said notches being provided with curved sides and curved bottoms, said curved sides adapted for engagement with the short edge of said binding, and integral means projecting from the face of the card adapted for engagement with the long edge of the said lining.

This specification signed and witnessed this 21st day of December, 1912.

EMIL HARDT.
